UNITED STATES PATENT OFFICE

JOHN W. C. MILLER, OF ROANOKE, VIRGINIA

COMBINED LIGHTING AND SIGNAL SWITCH FOR AUTOMOBILES

Application filed January 9, 1930. Serial No. 419,597.

The invention relates to a combination switch for automobiles, including a circuit closer of the push button type for controlling the audible signal, which circuit closer includes a slideable cap movable in any lateral direction with respect to the center of an insulating base, which latter carries the fixed contacts for the various light, signal and battery connections, a sliding contact plate which is connected with the slideable cap of the circuit closer to be moved by the latter for selectively controlling the light circuits and for maintaining the signal circuit in proper relation to be closed by the button or equivalent manually operated device, at all times.

The invention is illustrated in the accompanying drawings, in which:—

Fig. 1 is a plan view of the switch with a portion broken away.

Fig. 2 is a side elevation thereof.

Fig. 3 is a section on line 3—3 of Fig. 1.

Fig. 4 is a plan view of the switch with the cover removed, certain of the parts being shown in section.

Fig. 5 is a bottom plan view.

Fig. 6 is an enlarged view generally similar to that shown in Fig. 3, except that the section is diverted at the right hand of the base to show the terminal for connecting the signal circuit.

Fig. 7 is a plan view of the switch plate.

Fig. 8 is a plan view of the lower element of the insulating base.

Fig. 9 is a section on line 9—9 of Fig. 4.

Fig. 10 is a sectional elevation of a modified form of the switch.

Fig. 11 is a view similar to Fig. 4.

Fig. 12 is a view similar to Fig. 8.

Fig. 13 is a bottom plan view of the upper member of the insulating base.

Fig. 14 is a diagrammatic plan view of the first form of the switch, including the circuits to the various translating devices.

Fig. 15 is a similar view of the second modification.

Referring to the drawings illustrating the first modification, 1 indicates the bottom member of an insulating base preferably in the form of a disk, having formed in its top

surface a shallow recess or depression 2 having the general configuration of an arrow head, in the center of which is a second depression 3, which is generally rectangular, in which is secured a stationary contact plate 5 provided with depressions 6, one of which is centrally disposed and one each disposed in each of the corners of the substantially rectangular plate 5, said plate having an arm 7, preferably embedded in the base 1 and extending toward the periphery of the disk, the outer end of the arm 7 being engaged by a terminal stud or screw 53 adapted to be connected to a wire or conductor leading to the horn or other audible signal.

About the periphery of the base member 1 is disposed a series of openings 10, 11, 12, 13, 14, 15 and 16 and two diametrical opposite openings 19, the first of which is designed to receive the binding post 53 and the series 11 to 16 forming the passages for the conductor wires from the various fixed contacts, to be hereinafter described, and the openings 19 adapted to receive the screws by means of which the upper insulating member of the base is secured to the lower member 1, and both members are secured to the automobile.

The upper member of the base 30 is a disk of insulating material, having a central, generally rectangular opening 32 and provided on its upper face with spacing bosses 31. Adjacent the central opening 32 are two parallel spaced slots 33 through which project the bent ends of a conductor strip 34, which is fastened to the base by a stud or binding post 35, which constitutes the battery terminal of the switch, the bent ends of the conductor 34 passing through the slots 33 for engagement with a sliding contact plate, to be hereinafter described.

Near the periphery of the disk 30, there is provided a series of openings 10', 11', 12', 13', 14', 15' and 16' and two openings 19' corresponding to the openings in the bottom member 1, the opening 10' passing or permitting the passage of the terminal binding post 53 and the openings 11' to 16' registering with the openings 11 to 16 in the bottom plate and permitting passage of the various conductor wires of the light circuits.

Disposed in substantially triangular arrangement about the center of the disk 30 are three openings 39, 43, 51, and a fourth opening 47 is located in substantially axial alignment with the center and the opening 43 and between the latter and the periphery of the disk, said openings being adapted to permit the hemispherical bosses on the ends of the spring contact members to pass therethrough 5 and project within the recess 2 in the top of the bottom member 1, in position to be engaged by the sliding contact plate to be hereinafter described. The spring contacts are disposed in convenient relation, preferably 10 that shown in Fig. 4, the contact 36 being secured to the top of the disk 30 by a set screw 37, which also constitutes a terminal for the conductor wire leading to the bright lights, the free end of the spring conductor 36 having secured thereto a generally hemispherical boss 38, which projects through the opening 39. Spring contact 41 is similarly secured 15 to the base by a set screw 40, which constitutes a terminal connector for the lead to the tail light and the boss 42 on the end thereof projects through the opening 43 in the disk. Spring contact 45 is secured to the base by screw 44, which constitutes the binding post for connection with the wire leading to the 20 dim lights and the boss 46 on the end of the contact 45 projects through the opening 47. Spring contact 49 is connected to the base by screw 48, which is connected to the side lights and the boss 50 on the end of said spring contact projects through the opening 51 in the disk 30. By reference to Figs. 4 and 8, it will be seen that the wire from the binding post 53 passes through the registering openings 11' and 11 in the upper and lower members 25 30 and 1 of the base, the lead from binding post 40 passes through the registering openings 12' and 12, that from binding post 44 passes through the registering openings 13' and 13, that from binding post 48 passes 30 through registering openings 14' and 14, and that from binding post 37 through registering openings 16' and 16, while the lead from terminal 35 passes through registering openings 15' and 15. 35

Sildably mounted in the recess 2 in the bottom member 1 of the base is a contact plate 60 of the general form illustrated in Fig. 7, comprising an end portion 61 generally triangular in shape having lateral portions 62 and 63 extending beyond the body, the end portion 61 having formed therein an enlarged circular opening 64 and the opposite end being provided with an elongated slot 65 through which passes the binding post 60 35, which, as explained, constitutes the battery terminal of the switch, said binding post serving as a pivot about which the plate 60 may be oscillated or slid in the recess 2 of the base member 1. Projecting from the center 40 of the sliding plate 60 is a sleeve 66, which

is screw threaded on its outer end and is provided with a flange or shoulder 67 intermediate its ends.

Enclosing the base members 1 and 30 is a casing 70 having an open bottom and a top 70 provided with an enlarged circular opening 71 through which the sleeve 66 projects.

Mounted on the top of the casing is a circular plate 72 of insulating material having a centrally disposed upwardly extending threaded flange 73, the plate 72 and flange 73 constituting the base member of the cap of a circuit closer of the push button type, the other member of the cap being a collar 74 of insulating material having the usual projecting flange at its top to retain the metal lined button 75, which is adapted to be depressed to close the circuit to the horn or other audible signal. The cap of the push button or circuit closer is secured to the sleeve 66 of the sliding switch plate 60 by means of a nut 68, which engages the outer screw threaded end of the sleeve and serves to lock the plate 72 of the cap in engagement with the flange 67 on the sleeve, as illustrated in Fig. 6, so that the plate 60 will partake of any normal sliding movements of the cap of the push button or circuit closer.

Slidably mounted within the sleeve 66 is a tubular member 77, which is provided with an integral double bend flange 76, which serves as a support for a helical spring 82, the lower portion of which bears on the flange and the upper portion engages the interior of the button 75 and normally holds the latter in its outer position. Fixed within the tubular member 77 is an insulating sleeve 78, in which is secured a metal pin 79 having a rounded lower head 80, which is fitted with an insulating ring 81, the sleeve 78 and the ring 81 serving to insulate the pin from the adjacent metallic parts. Spring 82 also exercises a yielding downward stress on sleeve 78 and the parts carried thereby.

The upper or outer end of the pin 79 projects slightly beyond the insulating sleeve 78 in a position to be engaged by the member 75 of the push button, when said member is depressed against the tension of the spring, thereby completing the electric circuit to the horn or audible signal device.

The top of the casing is preferably provided with suitably inscribed legends indicating the particular lights which will be energized when the sliding push button is moved in a given direction. These legends appear in the drawings as Side, All, Brt and Dim, indicating that the lights named will be on, when the push button has been moved on the casing toward the particular index. Surrounding the central opening in the casing is another special index marking, which is preferably in the form of an annulus 72' of contrasting color, which is normally obscured by the base plate 72 of the push but-

ton, but which is uncovered in part when the push button is moved laterally in any direction. In order to render this index marking visible, it is preferably white and 5 a portion of the same will appear as a white crescent whenever the push button has been moved to close any of the light circuits. When all of the light circuits are open and 10 the push button is in neutral or central position, this annular band of contrasting color will be completely obscured.

The operation of the switch is diagrammatically exemplified in Fig. 14 considered in connection with Fig. 5. When the sliding contact plate 60 is in the position indicated in dotted lines in Fig. 14, all of the circuits to the various lights are broken, as said contact is out of engagement with all of the contacts 38, 42, 46 and 50, the battery 20 140 is, however, permanently connected to the sliding contact plate 60 by lead 141, contact screw 35 and the contact bar 34, so that the circuit to the audible signal may be closed at all times by depressing the member 75 of 25 the push button, thereby completing the circuit to battery 140, lead 141, terminal 35, contact bar 34, sliding contact plate 60, sleeve 66, spring 82, push button 75, pin 79, fixed contact plate 5, conductor 7, terminal 53, lead 30 142, horn 143, to the ground and back to the grounded side of the battery. In order to energize the bright lights and the tail light, the sliding contact plate 60 is moved downward from the position shown in Fig. 14, by 35 sliding the push button toward the designation Brt, as shown in Fig. 1, thereby causing the sliding contact plate 60 to pivot on the binding post 35 and move into engagement with the contact 38. This movement 40 also carries the hole 64 out of registry with the contact 42 and causes the latter to engage the contact plate 60, thereby establishing a circuit from the battery through the bright lights as follows: Battery 140, lead 45 141 to contact plate 60, as before, contact 38, lead 144 to the bright lights, thence by way of the ground connections back to the battery. The circuit from the battery to the tail light is, battery to plate 60, as before, 50 contact 42, lead 150, tail light 151 to ground. If it is desired to use the side lights, together with the tail light, the sliding contact plate 60 is swung upward from the position shown in Fig. 14 to engage contact 50 and also to 55 engage contact 42 of the tail light. The circuit will then be from the battery to the contact plate 60, as before, contact 50, lead 148 to side lights 149 to the ground back to battery and the tail light circuit will be as hereinbefore described. If it is desired to 60 use the bright, side and tail lights simultaneously, the contact plate 60 is slid to the right by moving the push button in the direction of the legend All, thereby bringing the sliding contact plate into engagement with the

contacts 38, 50 and 42, which completes the circuits hereinbefore described to the bright and side lights and also to the tail light. When the dim lights are desired, the sliding contact plate 60 is moved to the left, as shown 70 in Fig. 14, by sliding the push button toward the legend Dim, as indicated in Fig. 1, which causes the contact plate to engage contacts 46 and 42, so that the circuit to the dim lights will be from the battery, lead 141 to contact plate 60, as before, contact 46, lead 146, dim lights 147 and ground back to battery. As the contact plate 60 is also in engagement with contact 42, the tail light will be energized. It will thus be seen that, by the proper 80 sliding adjustment of the push button, the bright and side lights may be energized independently or simultaneously or the dim lights may be energized, under all of which conditions the tail light will also be energized and the sliding contact plate 60 will be held in any of its adjusted positions by the convex head of the pin 79 engaging the corresponding depression 6 in the fixed contact plate 5. It will also be seen that the 85 horn or audible signal may be operated for any and all positions of the push button, as the pin 79 associated therewith is always in engagement with the contact plate 5, which is directly connected in the horn circuit, as 90 hereinbefore described.

The switch is adapted to be mounted on the steering post or other suitable location on an automobile and the various wiring connections are taken in through the registering openings in the upper and lower members of the base. The device, therefore, not only involves simplicity and facility in control of the various lights and the audible signal, but lends itself to ready application 100 to various types of steering wheels employed in automobiles, on which the usual type of push button for controlling the horn or audible signal is mounted, as the switch may be substituted for the push button.

In the modification shown in Figs. 10 to 13, the same general characteristics of operation are involved and the device differs from that heretofore described in structural details only. The base comprises a bottom member 100, which is provided with a countersunk contact plate 105 having the same type of depressions 106 as the fixed contact plate 5 in the first modification, which contact plate is connected to terminal nut 108 by metallic strip 107, the nut being engaged by a screw or binding post 108'. Let into the top surface of the bottom member 100 is a conductor ring 109, which is in electrical connection with terminal nut or socket 110, which is engaged by a screw or binding post 110', which constitutes the terminal for the tail light connection.

The upper member 130 of the base is separated from the lower member by spacer lugs 130

or walls on the latter, not shown, in order to provide a free space between the members. The upper member has an enlarged central opening similar to that in the preceding modification, which opening is surrounded by a countersunk conductor plate 133, on the lower face of the member, which is similarly apertured and is connected by conductor strip 134 to terminal nut or socket 135, in which is mounted the set screw or binding post 135', which constitutes the terminal of the lead to the battery. Concentric with the plate 133 are two arcuate conductor strips 136, 138, which are countersunk in the lower face of the upper base member, as indicated in Figs. 10 and 13 and are connected to terminal nuts or sockets 137 and 139, respectively, which are engaged by screws or binding posts 137' and 139', which constitute the terminals for the bright and side light wires from the switch. Midway between the ends of the arcuate strips 136 and 138 is a contact 140, which is also countersunk or recessed into the lower face of the base member 130 and is connected with a terminal nut or socket 141, which is engaged by screw or binding post 141', which constitutes the terminal connection for the lead to the dim lights. As a matter of convenience in making the wiring connections, the upper base member 130 is provided with a peripheral depression 131, through which the various binding posts pass and both of the members 100 and 130 are provided with aligning openings near the peripheral edges thereof, through which the conductor wires are led and in which the screws for connecting the base members engage, in substantially the same manner and form shown in the preceding modification. The base members are enclosed in a casing 170, similar, in all respects, to the casing shown in the first modification, having a central opening corresponding with the opening in the upper member 130 of the base and slidably mounted on the casing is a push button similar to that hereinbefore described, including a base plate 172 having a vertically threaded flange 173, which is engaged by cap 174, which retains the button or finger piece 175, which is held in its outward position by a helical spring 182.

The push button is locked to a sliding member 160, which is of inverted cup shape and lies within the space between the upper and lower base members. Extending from the center of the member 160 is a sleeve 166, which is locked to the base member 172 of the push button by a nut similar to that in the preceding modification. A metallic sleeve 177 fits within the sleeve 166 and is provided with a flange 176, which forms the lower abutment for the spring 182. Within the sleeve 177 is an insulating sleeve 178 and mounted within the latter is a pin 179 similar, in all respects, to the pin 79 in the preceding modification,

the lower end 180 of which is rounded and is adapted to engage the several depressions 106 in the fixed contact plate 105 to hold the switch in its various positions of adjustments and also to form a connecting element in the circuit between the push button and horn. Closely surrounding the sliding member 160 is a helical spring 161, which is of substantially the same diameter as the fixed contact plate 133 and is, therefore, sufficiently large to engage the plate 133 and any of the other fixed contacts 136, 138 and 140, as the push button is adjusted to its various positions for energizing the bright lights with the tail light, the side lights with the tail light, both the bright lights and the side lights with the tail light, or the dim light with the tail light, and also to engage the conductor ring 109 in the bottom member of the base to complete the tail light circuit simultaneously with the closing of the circuits to any and all of the other lights.

The operation of this modification is practically the same as that in the first form of the device and will be understood from the diagram shown in Fig. 15. When the push button is in central or neutral position, all of the light circuits are open, as the sliding member 160 and the spring carried thereby is in central position and, therefore, out of engagement with all of the stationary contacts in the lighting circuits. As in the case of the first modification, the pin 179 connected with the push button is continuously in engagement with the fixed contact plate 105, so that the circuit to the horn can be closed in any and all positions of adjustment of the switch. When the push button is moved to bring the sliding spring contact 161 into engagement with fixed contact 136, the circuit to the bright lights is closed as follows: Battery 140', lead 141, binding post 135', conductor 134 to fixed contact plate 133, spring 161 to fixed contact 136, binding post 137', lead 144', lamps 145' to ground. At the same time, the circuit to the tail light is closed by the engagement of the spring contact 161 with fixed contact ring 109, the circuit being completed through binding post 110', lead 150' through the rear or tail light 151' to ground. When the sliding contact is moved by the push button to engage fixed contact 138, the circuit is closed through the side lights 149' as follows: Battery 140', lead 141, binding post 135', conductor 134, fixed contact plate 133, spring contact 161, fixed contact 138, binding post 139', lead 148', through the side lamp 149' to the ground. When the push button and the sliding spring contact are moved to the right, in the arrangement of the apparatus as shown in Fig. 15, the spring contact 161 engages both fixed contacts 136 and 138 and the parallel circuits are closed through the bright lights, the side lights and the tail light, said circuits being

those hereinbefore described. When the sliding contact is moved to cause the spring member 161 to engage fixed contact 140, the circuits to the dim lights and the tail light are closed, the tail light circuit being that described and that to the dim lights being as follows: Battery, lead 141', binding post 135, conductor 134, plate 133, sliding spring contact 161, fixed contact 140, binding post 141', lead 146 through the dim lamps 147' to the ground.

Both forms of the invention as described, therefore admit of the selective control of the lights and the operation of the audible signal by the manipulation of the push button. When the latter is in central or neutral position, all of the lighting circuits are interrupted, but, by sliding adjustment of the push button to the various positions hereinbefore indicated, the circuits to the bright lights and the tail light, the circuits to the bright lights, the side lights and the tail light, or the circuits to the dim lights and the tail light, respectively, may be closed. In addition to the legends on the top of the casing of the switch to indicate which of the light circuits are closed, a further indication is afforded by the uncovering of a portion of the annular band 72' of contrasting color by the base plate of the push button, the particular position of the crescent-shaped section of the band which is exposed indicating not only that some of the lights are on, but the particular light circuits which are closed by the switch.

What I claim is:

1. A switch for controlling the lights and audible signal of automobiles, comprising an insulating base including upper and lower sections, fixed contacts for bright, dim, side and tail light, battery and signal connections carried by the base, a push button slidably mounted relatively to the base, a contact member slidably mounted between the sections of the base for selectively engaging the fixed contacts for the lights, and means connecting said contact member with the push button for conjoint sliding movement therewith.

2. A switch for controlling the lights and audible signal of automobiles, comprising a base including upper and lower sections, a circuit closer slidably supported relatively to the base, light circuit and battery contacts on the base, a contact member slidably mounted between the sections of the base for selectively engaging the contacts for the lights, and means connecting said contact member with the circuit closer for conjoint sliding movement therewith.

3. A switch for controlling the lights and audible signal of automobiles, comprising a base including upper and lower sections, a circuit closer of the push button type for the signal having a cap slidably mounted relatively to the base, fixed contacts for the bright, tail and side light, signal and battery connections on the base, a contact member slidably mounted between the sections of the base for selectively controlling the light circuits, and means connecting the contact member with the sliding cap of the circuit closer to effect conjoint sliding movement of said elements.

4. A switch for controlling the lights and audible signal of automobiles, comprising a base including upper and lower sections, fixed contacts for bright, side and tail light, signal and battery connections on the base, a contact member slidably mounted between the sections of the base for selectively controlling the light circuits, a circuit closer of the push button type slidably supported relatively to the base, and means connecting the contact member with the sliding cap of the circuit closer to effect conjoint sliding movement of said elements.

5. A switch for controlling the lights and audible signal of automobiles, comprising a base including upper and lower sections, fixed contacts for bright, side and tail light, signal and battery connections on the base, a contact member slidably mounted between the sections of the base for selectively controlling the light circuits, a circuit closer of the push button type slidably supported relatively to the base, and means connecting the contact member with the sliding cap of the circuit closer to effect conjoint sliding movement of said elements.

6. A switch for controlling the signal elements of automobiles, comprising an insulating base including upper and lower sections, fixed contacts for connections to the signal elements and the battery carried by the base, a push button slidably mounted relatively to the base, a contact member slidably mounted between the sections of the base for selectively engaging certain of said fixed contacts to close the circuits from the battery to the desired signal elements, means for connecting the contact member with the push button for conjoint sliding movement therewith, and means interposed between the push button and one of the fixed contacts to close the circuit to another of said signal elements when the push button is depressed.

7. A switch for controlling the light and audible signals of automobiles, comprising an insulating base including upper and lower sections, fixed contacts for light signals, audible signal and battery connections on the base, a push button slidably mounted relatively to the base, a contact member slidably mounted between the sections of the base for selectively engaging the fixed contacts for the light signals to close circuits from the battery to the desired light signals, means connecting the contact member with the push button for conjoint sliding movement therewith, and means interposed between the push button and one of the fixed contacts to close the circuit to the audible signal when the push button is depressed.

8. A switch for controlling the lights and audible signal of automobiles, comprising an insulating base including a lower section and an upper section, the latter having a central opening, fixed contacts for bright, dim, side and tail light, battery and signal connections carried by the base, the signal contact being centrally located on the upper face of the lower section, terminal connectors for said contacts, a cover for the base hav-

- ing a central opening, a push button slidably mounted on the cover, a sliding contact member between the sections for selectively controlling the light circuits, a sleeve connecting the sliding contact member and the push button, and a pin in said sleeve engaging the signal contact on the lower section and engageable by the push button to close the signal circuit.
8. A switch for controlling the lights and audible signal of automobiles, comprising a two part insulation base including a lower section and an upper section, the latter having a central opening, fixed contacts for bright, side and tail light and battery connections carried by the upper member and extending through the latter, a fixed contact for the signal on the upper face of the lower section, terminal connections for said contacts, a cover for the base having a central opening, a push button slidably mounted on the cover, a sliding contact member between the sections for selectively controlling the light circuits, a sleeve connecting the sliding contact member and the push button, and a pin in said sleeve engaging the signal contact on the lower section and engageable by the push button to close the signal circuit.
9. A switch for controlling the lights and audible signal of automobiles, comprising a two part insulation base including a lower section and an upper section, the latter having a central opening, fixed contacts for bright, dim, side and tail light and battery connections disposed about the center of the upper section and extending through the latter, a fixed contact for the signal on the upper face of the lower section, terminal connections for said contacts, a cover for the base having a central opening, a push button slidably mounted on the cover, a sliding contact member between the sections for selectively controlling the light circuits, a sleeve connecting the sliding contact member and the push button, and a pin in said sleeve engaging the signal contact on the lower section and engageable by the push button to close the signal circuit.
10. A switch for controlling the lights and audible signal of automobiles, comprising a two part insulation base including a lower section and an upper section, the latter having a central opening, fixed contacts for bright, dim, side and tail light and battery connections disposed about the center of the upper section and extending through the latter, a conductor plate for the signal circuit fixed in the upper face of the lower section, terminal connectors for the several contacts, a cover for the base having a central opening, a push button slidably mounted on the cover, a sliding contact plate between the sections for selectively controlling the light circuits, a sleeve connecting the sliding contact plate and push button, an insulated pin in said sleeve engaging the signal contact on the lower section and engageable by the push button to close the signal circuit.
11. A switch for controlling the lights and audible signal of automobiles, comprising a two part base of insulation including a lower section having a central fixed contact plate provided with central and laterally disposed depressions, an upper section having a central opening, fixed contacts for bright, dim, side and tail light and battery connections carried by the upper member disposed about the central opening therein, terminal connectors for said contacts, a cover for the base having a central opening, a push button slidably mounted on the cover, a sliding contact plate between the sections for selectively connecting the light contacts with the battery contact, a sleeve on the contact plate secured at its end to the push button, and an insulated pin in the sleeve having a head on its inner end to engage the depressions in the fixed contact plate and its outer end positioned for engagement by said push button.
12. A switch for controlling the lights and audible signal of automobiles, comprising a lower base member having a recess in its top, a centrally disposed countersunk fixed contact plate in said recess having central and laterally disposed depressions therein, a terminal connected to said plate, an upper base member having a central opening, fixed contacts for bright, dim, side and tail light and battery connections carried by and passing through said upper member, terminals connected to said contacts, a slidable contact plate in the recess in the lower base member cooperating with said fixed contacts on the upper base member to selectively control the lights and having a slot traversed by one of said terminals, a sleeve fixed to the top of said slidable plate, a cover for said base members having a central opening, a slideable push button on said cover above said opening, means for securing the push button to said sleeve, and an insulated pin in said sleeve having a convexed head on its lower end engaging the fixed contact plate and cooperating with the depressions therein to hold the slidable contact plate in its various positions of adjustment, and the upper end of said pin in engageable relation with the push button.
13. A switch for controlling the lights and audible signal of automobiles, comprising an insulation base, fixed and movable contacts carried by the base for selectively controlling the lights, a cover for the base having a central opening therein, a push button slidably mounted on the cover over the opening, means for connecting the push button to the movable contact on the base to effect corresponding movements of those members, and an index marking on the cover below the push button covered by the latter when in central

position and uncovered in part when the push button is in any position of lateral adjustment.

14. A switch for controlling the lights and audible signal of automobiles, comprising an insulation base carrying light, signal and battery contacts, a sliding contact member carried by the base for selectively connecting the light and battery contacts, a cover 10 for the base, a push button slidably mounted on the cover for closing an audible signal circuit, connections between the push button and slidable contact member to effect concurrent movement of said parts, and an index 15 marking on the cover below the push button covered by the latter when in central position and uncovered in part when the push button is in any position of lateral adjustment.

In testimony whereof I affix my signature.

20 JOHN W. C. MILLER.
